UNITED STATES PATENT OFFICE.

GEORGE WILLIAM ANDERSON, OF JACKSONVILLE, FLORIDA, ASSIGNOR TO HARRY G. ANDERSON, OF CARBUR, FLORIDA.

COMBINED CHAIR AND IRONING-TABLE.

1,250,755.

Specification of Letters Patent. Patented Dec. 18, 1917.

Application filed November 24, 1914, Serial No. 873,815. Renewed May 23, 1917. Serial No. 170,564.

To all whom it may concern:

Be it known that I, GEORGE WILLIAM ANDERSON, a citizen of the United States, residing at Jacksonville, in the county of Duval and State of Florida, have invented new and useful Improvements in Combined Chairs and Ironing-Tables, of which the following is a specification.

My invention relates to a combined chair and ironing table, the object of the invention being to provide an article of furniture of this character which when not in use may be disposed and employed in the form of a chair, and which, when disposed for use as an ironing table, will efficiently subserve this function.

A further object of the invention is to provide an article of the character described wherein the parts of the table proper are adapted to fold against and parallel with the seat back, and wherein the seat back is adjustable to form a part of an extended table, if desired.

The invention consists of the features of construction, combination and arrangement of parts herein fully described and claimed, reference being had to the accompanying drawings in which:—

Figure 1 is a side elevation showing the device in folded or collapsed condition, and as adapted for use as a chair.

Fig. 2 is a side elevation showing the device as arranged for use as a short ironing table.

Fig. 3 is a similar view showing the device as adapted for use as a long ironing table.

Fig. 4 is a vertical section through the chair and folded table as illustrated in Fig. 1.

Figs. 5 and 6 are cross sections through the table on lines 5—5 and 6—6 of Fig. 3, looking toward the chair and stand respectively.

Fig. 7 is a horizontal section through the stand, taken on a line immediately above the braces and latch bar.

Fig. 8 is a bottom plan view of the table showing the stand in folded position.

Fig. 9 is a detail view showing the sleeve board adjusted for use.

Referring to the drawings, 1 designates a chair body of any suitable or preferred construction, the same including a rear upright 2 and a back 3. The uprights 2 are con-

nected at their upper ends by a guide rod 4, and the rear surface of the back 3 is provided at its sides with slotted longitudinally extending guide members 5 engaging said guide rod. By this construction the chair back is mounted for sliding and pivotal motions on the cross rod so that it may be disposed in a normally vertical position to form the back of the chair or adjusted outwardly and then tilted rearwardly to a horizontal position to form a component part of the ironing table, as hereinafter described. A cross cleat 6 is provided upon the chair seat for engagement with the lower edge of the back to hold the same from forward swinging movement when in normal position.

The normal upper edge of the back 3 is normally projected above the upper ends of the uprights 2 and is provided upon its rear face with spacing blocks or members 7. These spacing blocks or members are adapted to abut against and coöperate with spacing blocks or members 8 upon the inner edge of an ironing board 9, which is hinged 80 connected by hinge members 10 to the upper end of the seat back, the leaves of said hinge members being respectively attached to the spacing blocks or members 7 and 8, as shown. The board 9 is adapted when not in use to 85 be turned down to a vertical position at the rear of the chair in parallel relation to the seat back, and is provided with a lateral projection 11 at its lower end for engagement with a latch 12 on the chair frame, 90 whereby said boards and the parts carried thereby may be fastened in folded position.

The outer end of the board is adapted when disposed in horizontal position to form an ironing table to be supported by a folding stand comprising inner and outer pairs of legs 13 and 14 pivotally connected at their upper ends by a pin 15. The legs 13 are connected at their lower ends by a cross rod or round 16, while the legs 14 are connected 100 at their lower ends by cross braces or strips 17. A latch bar 18 is hinged to the round 16 and is provided with a notched free end 19 to engage the braces 17 at their crossing angle, so as to hold the legs spread to form 105 a stand to support the ironing board in a firm and stable manner. Blocks 20 are secured to the under side of the outer end of the board 9 and are formed with cross grooves 21 pivotally receiving the pin 15, 110

which is engaged and held seated in said grooves by a latch dog 22. This dog 22 is carried by a board, plate or strip 23 slidable longitudinally of the board in guide ways 5 formed by the blocks 20, so that the dog may be slid into and out of engagement with the pin 15, to engage or release said pin to connect the stand with the board or disconnect it therefrom, as will be readily understood. 10 Fig. 1 shows the device in use as a chair, from which it will be seen that the board 9 hangs pendent at the back of the chair and is secured by the latch 12, while the stand in folded condition is retained between said 15 board and the seat back 3, and is inclosed in the space between the slotted guides 5. When it is desired to employ the ironing board, the latch 12 is released and the ironing board swung outward, after which the 20 legs are unfolded and swung outward to a vertical position and locked in spread condition by the latch 18 to provide a stand to support the outer end of the board, the inner end of which is supported by its 25 hinged connection with the upper end of the seat back 3. If it should be desired to extend the length of the board, this may be done by sliding the seat back 3 upward and throwing it downward to a horizontal position, as shown in Fig. 3. In folding the 30 board the latch 18 is released, the legs 13 and 14 are folded together and swung upward against the under side of the board, and the latter is then swung back to the 35 normal position shown in Fig. 1 parallel with the seat back and secured again by the latch 12. The device will then be disposed in the form of a chair and therefore may be arranged in a compact position in a room. 40 or apartment and used to perform the function of an article of ordinary furniture. The board 23 is designed to be drawn outward, as shown in Figs. 3 and 9, to serve

as a sleeve board or supplemental board for ironing and pressing sleeves, the waist portions and shoulders of garments and other small work. 45

From the foregoing description, taken in connection with the drawings, the construction, mode of operation and advantages of 50 my improved combined chair and ironing board will be readily understood, and its conveniences appreciated. It will of course be obvious that while the construction shown is preferred modifications may be made 55 within the scope of the invention without departing from the spirit or sacrificing any of the advantages thereof.

I claim:—

1. A device of the character described 60 comprising a chair frame having uprights, a seat back slidably and pivotally engaging said uprights, a board hinged at one end to said seat back, a folding stand pivoted to the other end of the board, and means for 65 holding the board and stand in collapsed condition against the rear surface of the seat back.

2. An article of the character described 70 comprising a chair frame including uprights connected at their upper ends by a cross rod, a seat back having slotted guides slidably and pivotally engaging said cross rod, a board hinged at one end to the upper end of the seat back, a folding stand hinged to 75 the other end of the board and adapted to be folded parallel therewith and between the board and seat back, and a means for securing the board in depending position 80 parallel with the seat back.

In testimony whereof I affix my signature in presence of two witnesses.

GEORGE WILLIAM ANDERSON.
